PROCESS FOR CONVERSION OF $3\beta,17\alpha$ -DIHYDROXY-5-PREGNENE-11,20-DIONE TO CORTISONE ACETATE

Edward S. Rothman, Philadelphia, and Monroe E. Wall, Oreland, Pa., assignors to the United States of America as represented by the Secretary of Agriculture

No Drawing. Application March 4, 1958
Serial No. 719,170

2 Claims. (Cl. 260—397.45)

(Granted under Title 35, U.S. Code (1952), sec. 266)

A non-exclusive, irrevocable, royalty-free license in the invention herein described, throughout the world for all purposes of the United States Government, with the power to grant sublicenses for such purposes, is hereby granted to the Government of the United States of America.

This invention relates to a process for converting $3\beta,17\alpha$ -dihydroxy-5-pregnene-11,20-dione to cortisone acetate or cortisone.

An object of the present invention is to provide a process for proceeding from $3\beta,17\alpha$ -dihydroxy-5-pregnene-11,20-dione to cortisone acetate which eliminates the Oppenauer oxidation and, more especially, the protective acetylation of the 17α -hydroxyl group. The latter reaction and the subsequent de-acetylation to 17α -hydroxyl cause an appreciable yield lowering at the final stages of cortisone manufacture where high yields are most significant. Furthermore, during all the final reactions of the process of this invention the C-21 function is an acetoxy group, so it is not necessary to reacetylate the C-21 hydroxyl to obtain cortisone as its acetate, the usual product of commerce.

We have found that the desired Δ^4 -3 keto moiety of cortisone can be obtained by oxidizing 21-acetoxy- $3\beta,17\alpha$ -dihydroxy-5-pregnene-11,20-dione with chromic acid-sulfuric acid mixture in acetone medium. Not only is the dihydroxy acetone side chain stable under these conditions, but surprisingly, the undesirable rearrangements which often occur under acidic conditions did not take place. For example, undesired reactions such as fission of the entire easily-oxidizable dihydroxyacetone side chain, glycolic rearrangement of the 17α -hydroxyl group to the C-21 position to form a C-21 aldehyde group (known to occur when cortisone in methanolic hydrochloric acid is allowed to stand at room temperature) and D-homo rearrangement (D-ring expansion) did not occur.

The source material, $3\beta,17\alpha$ -dihydroxy-5-pregnene-11,20-dione, for the present process was prepared from 11-ketodiosgenin, as described in our copending application, Serial Number 644,184, filed March 5, 1957.

According to the present invention we brominate $3\beta,17\alpha$ -dihydroxy-5-pregnene-11,20-dione with two molecules of bromine thus to obtain 5,6,21-tribromo- $3\beta,17\alpha$ -dihydroxyallopregnane-11,20-dione. We then sequentially treat the product in acetone solution with sodium iodide and sodium or potassium acetate to obtain the new compound, 21-acetoxy- $3\beta,17\alpha$ -dihydroxy-5-pregnene-11,20-dione. Brief oxidation of this compound in acetone with chromic acid-sulfuric acid mixture gives a high yield of a new compound, isomeric with cortisone acetate, and differing from cortisone acetate only in the location of the double bond, viz. Δ^5 instead of Δ^4 . This new compound, 21-acetoxy- 17α -hydroxy-5-pregnene-3,11,20-trione, is easily isomerized to 21-acetoxy- 17α -hydroxy-4-pregnene-3,11,20-trione (cortisone acetate) by quite small (catalytic) amounts of acid or base, e.g. ammonia. The

2

improvements disclosed in this invention will be made clear by the following examples.

Example 1

5 *Preparation of 21-acetoxy- $3\beta,17\alpha$ -dihydroxy-5-pregnene-11,20-dione.*—Five grams of $3\beta,17\alpha$ -dihydroxy-5-pregnene-11,20-dione was dispersed in 300 ml. of chloroform and, during the course of 1.5 hours, one mole of bromine in 61.35 ml. of carbon tetrachloride was added. At this point the entire quantity of steroid had passed into solution. Although attack at C-21 seems to go preferentially over addition at 5,6 we prefer to add a second mole of bromine. It was sometimes necessary to add a little more chloroform in reactions where re-precipitation occurred or where turbidity developed. The second mole of bromine is taken up with some reluctance. At the end of the bromination solvents were removed in vacuo. The residue was dissolved in a liter of acetone and treated with 20 g. of sodium iodide with stirring at room temperature overnight. The steroids were isolated with ether and freed of iodine by very cautious treatment with a minimum of sodium thiosulfate solution. The solvents were again removed in vacuo and the steroids again dissolved in a liter of acetone containing 4 ml. of acetic acid and 20 g. of dry potassium acetate. The mixture was stirred at reflux for 12 hours and again steroidal matter was isolated with ether. The product was recrystallized from aqueous acetone to give needles de-solvating at 97°, and showing a double M.P. 112°, 208-213°, $[\alpha]_D^{25} = +33.0$.

Example 2

35 *Preparation of 21-acetoxy- 17α -hydroxy-5-pregnene-3,11,20-trione.*—A sample of the preceding preparation, 1.35 g., was dissolved in 250 ml. of acetone (redistilled from potassium permanganate), cooled to 12° C. and treated with 1 ml. of an aqueous solution of 0.2672 g. chromium trioxide and 0.23 cc. of sulfuric acid. The reaction proceeded rapidly and within a minute a gray precipitate formed. After an additional two minutes passed, the reaction was stopped by dilution with 600 ml. of saline solution. The green solution gradually deposited a residue of pure white, flattened needles which were filtered off, washed with saline solution and with water. A sample was recrystallized from aqueous acetone to give pure 21-acetoxy- 17α -hydroxy-5-pregnene-3,11,20-trione. The melting point depended somewhat on the rate of heating. Rapid determination on a preheated Kofler stage gave a value of 180-183° C. A slower determination gave 40 melting at 175° to a viscous mass that resolidified incompletely to short quadrangular forms reddening (decomposition) at 200° with final crystal disappearance at 220°. The sample was nearly transparent to ultraviolet 239 m μ . 45 The sample was nearly transparent to ultraviolet 239 m μ . 50 radiation. E=300 (methanol) without maximum. 55 $[\alpha]_D^{25} = +44.3$ ° (dioxane).

Example 3

60 *Preparation of cortisone acetate.*—A sample of 350 mg. of 21-acetoxy- 17α -hydroxy-5-pregnene-3,11,20-trione was dissolved in 50 ml. of methanol and 0.4 ml. of concentrated ammonia water ("28%") was added. The mixture was let stand 75 minutes and the steroid was precipitated by addition of saline. The product after crystallization 65 from aqueous methanol was cortisone acetate identical in every respect with authentic cortisone acetate.

Example 4

70 The isomerization was carried out identically with Example 3 except that the catalyst used was 0.4 ml. of 6 N HCl. The product was cortisone acetate.

We claim:

1. A process for converting $3\beta,17\alpha$ -dihydroxy-5-pregnene-11,20-dione to cortisone acetate comprising brominating $3\beta,17\alpha$ -dihydroxy-5-pregnene-11,20-dione to obtain 5,6,21-tribromo- $3\beta,17\alpha$ -dihydroxyallopregnane-11,20-dione, reacting the latter successively with sodium iodide and a reagent consisting of acetic acid and a salt selected from the group consisting of potassium acetate and sodium acetate, and recovering 21-acetoxy- $3\beta,17\alpha$ -dihydroxy-5-pregnene-11,20-dione, adding chromium trioxide-sulfuric acid mixture to a cold acetone solution of the 21-acetoxy- $3\beta,17\alpha$ -dihydroxy-5-pregnene-11,20-dione to oxidize the 3β -hydroxy function, recovering 21-acetoxy- 17α -hydroxy-5-pregnene-3,11,20-trione and allowing it to

stand in a medium selected from the group consisting of a basic alcoholic solution and an acidic alcoholic solution to isomerize 21-acetoxy- 17α -hydroxy-5-pregnene-3,11,20-trione to 21-acetoxy- 17α -hydroxy-4-pregnene-3,11,20-trione.

2. 21-acetoxy- 17α -hydroxy-5-pregnene-3,11,20-trione.
